AIR COOLING DEVICE

Fred A. Helfrech, Oakland, Calif.

Application October 8, 1937, Serial No. 167,988

16 Claims. (Cl. 62—169)

This invention relates to an air cooling device and more particularly to a portable type of air cooling device which would find advantageous use in cooling closed bodies of vehicles propelled by internal combustion engines, such as automobiles and airplanes and in individual rooms of homes, or hospitals, or in other situations where it is desirable to employ a device for lowering the temperature without the necessity for installation of an expensive air conditioning and cooling system.

10 Among the objects of the invention are to provide an air cooling device which is inexpensive in construction and efficient in operation, and which may be installed as an individual unit. 15 Another object is to provide an air cooling device especially adapted for installation in a closed body of a vehicle propelled by an internal combustion engine, and which may be operated responsive to the motor unit of the vehicle.

20 Since, in the operation of the device herein described, a source of suction is desired, and inasmuch as the intake manifold of an internal combustion engine furnishes such suction, the invention herein is described with relation to such 25 25 a source of suction, it being understood that if the apparatus is employed in different environments, the suction source could be any suitable well-known apparatus of the suction pump type.

With the foregoing and other objects in view, 30 the invention, broadly stated, consists of the novel features and novel combination of features of the mechanism herein disclosed, the one form described herein and illustrated in the accompanying drawing being by way of example of a 35 preferred form the invention may take, it being understood that changes in size, materials, proportion and details are contemplated as being within the scope of the invention and the appended claims.

40 Referring to the drawing:

Fig. 1 is a side view of an assembly of the apparatus as connected to a motor vehicle engine.

Fig. 2 is an enlarged detail view, partly in vertical section, of apparatus shown in Fig. 1.

45 Fig. 3 is an enlarged detail view of shut-off cock and valve shown in Fig. 1, being partly in vertical section.

Referring to the drawing in which like characters of reference indicate corresponding parts 50 in the several views, 10 is a tank or container for a volatile liquid or fluid 11, and preferably a motor fuel such as gasoline, naphtha, or the like with which the tank is filled to a predetermined level 12 spaced from the top of tank 10, at which point the liquid is maintained by a float 13, pivotally

mounted as by pin 14 adjacent an outlet end opening 16 of an intake conduit member 15 which communicates with a filling opening 10a. The terminal end opening 16 of the intake conduit 15 is controlled by a slidably cut-off or float valve 17, which may be of a type having a ball seated in a pocket or recess 18, and the opening and closing of which is controlled by the rise and fall of float 13. The float 13 is pivotally supported by the float bar 19 by which the ball of valve 17 is maintained in its recess or pocket. Downward movement of the float 13 and bar 19 is limited by a stop means such as pin 20 and thereby prevents the ball valve 17 from becoming dislodged from its pocket, though permitting the 15 unseating of the valve so that the intake conduit is opened when the float 13 drops downward responsive to lowering of fluid in the tank below the predetermined level. It is also obvious that the intake conduit is closed or cut off responsive to 20 the raising of the float 13 by the fluid in the tank.

Automatically operable means are provided for supplying liquid to the tank 10. Connected to the intake conduit 15 at the filling opening 10a 25 is a feed line conduit 21 which has its opposite end immersed in or accessible to a suitable supply of volatile fluid. In the illustrated exemplification of the invention as employed in a motor vehicle, the feed line 21 connects with the gasoline line fuel supply line 21a of the motor vehicle preferably adjacent the carburetor 22 of the motor where it is readily accessible, and at which point there may be provided a means such as cock 22a for completely disconnecting the air cooling 30 device from the gasoline feed line. A check valve 22b having a very small by-pass 22c is provided at the cock 22a so that the liquid remaining in feed line 21, when valve 17 closes, may be returned slowly to the fuel supply line of the engine. 40

Means are provided for introducing air into the tank 10 preferably adjacent the bottom thereof, said means as illustrated herein comprising an air pipe 23 which may be stabilized fixedly within the tank by mounting same in connection 45 with both top and bottom of the tank. Adjacent the lower end of the air pipe 23, or in any event, below the predetermined level 12 of the fluid in the tank, are air vents 24. At the upper end of the air pipe 23 is an intake opening 23a controlled by a one-way check valve 25 actuated to its seat by resilient coil spring 26 which is mounted about coil stem 27, and the resilience of which may be adjusted by nut 28 which rests on washer 29.

A suction vent 30 is provided in the upper end 55

of the tank, to which there is connected a suction conduit 31 which in turn has connection to any suitable suction source. In the exemplification illustrated herein, the suction source is the intake 5 manifold 31^a of the vehicle motor 31^b, to which the suction conduit 31 is connected above the carburetor 22 so that gases of evaporation in the tank may be disposed of through the motor in an economical and safe manner by adding same 10 to the carburetted fuel which is employed to operate the motor. It is to be understood that if the cooling unit is employed in an environment other than a motor vehicle, the suction line 31 may be connected to any suitable type of suction 15 pump.

Intermediate the ends of the suction conduit there is provided a suction control valve generally indicated 32. The suction control valve 32 may be supported in any suitable manner in the 20 suction conduit line, and, as illustrated in connection with installation of the device in a motor vehicle body, is mounted so as to be accessible for operation from the panel board 33 in the driver's compartment. For this purpose the portion 34 of the suction line is formed so as to provide a supporting bracket for valve 32 and includes a depending arm 35. The bracket portion 34 has an opening 36 therethrough providing a seat for a suction control valve 37 which may comprise 30 a conical valve body maintained tightly, but turnably, on its seat by coil spring 38 buttressed against nuts 39 which are threadedly mounted at the inner end of the valve body. An opening or orifice 40 is provided through the valve body for 35 registering with the conduit of the suction line. The opposite or outer end of the suction control valve body extends through an opening 41 in the panel board and mounts a hand grip member 42 by which said valve body may be rotated so as to 40 manually and selectively open and close the suction line conduit. An automatically operating means for control of the suction line is also provided, such as an expansion plate thermostat 43 mounted at its axial center on a bar or shaft 44 45 which projects from one face thereof and is threadedly mounted for advancement and retraction in arm 35 of the bracket. The thermostat is advanced and retracted by means of a rod 45 connected thereto and which is rotatably 50 mounted in an opening longitudinal of the suction valve body. The rod 45 is also longitudinally slidable in said opening of the suction valve body and is provided with an annular groove 46 closely adjacent the orifice 40 of the valve body. 55 It will be observed that when the thermostat automatically expands and contracts responsive to the temperature variations of its environment, it will actuate the annular groove 46 into and out of register with the orifice 40, thus automatically 60 controlling the suction line so long as the valve 37 and its orifice 40 are in open position. When the valve 37 is manually turned to closed position, the suction line will be completely inoperative. The thermostat adjustment rod 45 is 65 provided at its outer end with a knob 47 by which the thermostat 43 may be manually advanced and retracted for adjusting the effectiveness of the thermostat to automatically open and close the suction line at various temperatures. For 70 purposes of extremely exact control of the suction line, it is preferred that the groove 46 be V-shaped with one wall perpendicular and the other wall on an oblique angle thereto, as shown in the drawing. As a guide in regulating the 75 valve 32 and thermostat 43, a dial 48 is provided

on the panel board having proper calibrations by which the hand grip 42 and knob 47, respectively, may be conveniently set or adjusted from the driver's seat. A manually operable cock 49 is provided at the bottom of tank 10 for emptying 5 same when and if desired.

The mode of operation of the apparatus is as follows:

Upon operation of the suction source through the suction conduit 31, a state of partial vacuum will be set up in the tank 10. Assuming the tank to be empty or that the supply of liquid is below the predetermined level, the float 13 will be in its down position, thus releasing the float valve 17. Since the air inlet 25 is spring-loaded to its closed 15 position, the vacuum in the tank will initially draw fluid from the fluid supply into the tank until the predetermined fluid level is reached, at which time the float 13 will close the valve 17 and thereafter the vacuum or suction will be effective to open the air valve 25 against the resistance of the coil spring 26. The effect of this will be to permit air to enter the tank through the air pipe 23, and be discharged at the bottom of the liquid supply through the openings 24, 25 whereupon the air rises to the top through the liquid, evaporating the same, and thereupon causing reduction of temperature of the tank and thus serving to effect its refrigeration function. When sufficient of the liquid has been evaporated 30 to drop below the predetermined liquid level, the float 13 automatically drops, opens the valve 17, and thereby re-charges the liquid supply to its pre-determined level. The thermostat 43, being manually adjustable as above described to operate varying temperatures, automatically retracts and advances the rod 45 so as to automatically place the groove 46 in register with the openings 40 of the suction control valve. When it is desired that the device shall not be operative, the 40 suction control valve 37 is rotated so that the openings 40 are not in register with the conduit of the suction line and thereupon the functioning of the device is discontinued. When the suction line is connected to the intake manifold of 45 an internal combustion engine, the gases of evaporation in the tank are carried to the intake manifold and are discharged through the cylinders of the motor wherein their fuel value may also be utilized. Possibility of any of the gases 50 of evaporation escaping into the room or vehicle body is eliminated by the one-way spring-loaded valve 25.

In the simple and more economical form of the apparatus it may be desired to dispense 55 with the automatic feed of liquid into the tank 10, in which event the float 13, feed conduit 15 and feed line 21 may be eliminated and the orifice 10^a used merely as a filling opening to charge the tank with the desired liquid.

The refrigeration area of the exterior of the tank may be increased by corrugating the wall thereof as shown in the drawing.

While I have expressed preference for use of a highly volatile liquid in the tank 10, it is to 65 be understood that I do not exclude the use of water therein since it will serve the purpose, but with a lesser degree of refrigerating efficiency.

I claim:

1. An air cooling device comprising a tank 70 for containing a fluid at a predetermined fluid level, an air inlet means for admitting air into the tank below the predetermined fluid level, a suction means for drawing air from above the fluid level in the tank, a valve for controlling 75

the suction of the air from the tank, and a thermostat for controlling said last mentioned valve.

2. An air cooling device comprising a tank for containing a fluid at a predetermined fluid level, 5 an air inlet means including a check valve for admitting air into the tank below the predetermined fluid level, a suction means for drawing air from above the fluid level in the tank, a valve for controlling the suction of the air from the tank, and a thermostat for controlling said last mentioned valve.

3. An air cooling device comprising a tank for containing a fluid at a predetermined fluid level, a supply conduit for communicating with a fluid 15 supply and with said tank, an air inlet means for admitting air into the tank below the predetermined fluid level, a suction means for drawing air from above the fluid level in the tank, a valve for controlling the suction of the air 20 from the tank, and a thermostat for controlling said last mentioned valve.

4. An air cooling device comprising a tank for containing a fluid at a predetermined fluid level, a supply conduit for communicating with a fluid 25 supply and with said tank, an air inlet means including a check valve for admitting air into the tank below the predetermined fluid level, a suction means for drawing air from above the fluid level in the tank, a valve for controlling the suction of the air 30 from the tank, and a thermostat for controlling said last mentioned valve.

5. An air cooling device comprising a tank for containing a fluid at a predetermined fluid level, a supply conduit for communicating with a fluid 35 supply and with said tank, a cut-off valve for controlling communication of the supply conduit with the tank, a float operative responsive to the fluid level in the tank for actuating the cut-off valve, an air inlet means for admitting air 40 into the tank below the predetermined fluid level, and a suction means for drawing air from above the fluid level in the tank, said air inlet means including a control valve adapted to keep the air inlet closed when the cut-off valve of the 45 fluid supply conduit is open, and to open the air inlet means responsive to the suction means when said cut-off valve is closed.

6. An air cooling device comprising a tank for containing a fluid at a predetermined fluid level, 50 a supply conduit for communicating with a fluid supply and with said tank, a cut-off valve for controlling communication of the supply conduit with the tank, a float operative responsive to the fluid level in the tank for actuating the cut-off valve, an air inlet means including a check valve for admitting air into the tank below the predetermined fluid level, a suction means for drawing air from above the fluid level in the tank, and a valve for controlling the suction of the air 55 from the tank, said check valve of the air inlet means being operative to maintain the air inlet closed when the cut-off valve of the fluid supply conduit is open, and to open the air inlet means responsive to the suction means when said cut-off valve is closed.

7. An air cooling device comprising a tank for containing a fluid at a predetermined fluid level, a supply conduit for communicating with a fluid supply and with said tank, an air inlet means 70 for admitting air into the tank below the predetermined fluid level, a suction means for drawing air from above the fluid level in the tank, and a valve for controlling the suction of the air from the tank, and a thermostat for controlling said last mentioned valve.

8. An air cooling device comprising a tank for containing a fluid at a predetermined fluid level, a supply conduit for communicating with a fluid supply and with said tank, a cut-off valve for controlling communication of the supply conduit with the tank, a float operative responsive to the fluid level in the tank for actuating the cut-off valve, an air inlet means including a check valve for admitting air into the tank below the predetermined fluid level, a suction 10 means for drawing air from above the fluid level in the tank, a valve for controlling the suction of the air from the tank, and a thermostat for controlling said last mentioned valve.

9. In a vehicle having a closed body compartment, the combination of an internal combustion motor unit provided with an intake conduit for fluid fuel, and an air cooling device comprising a tank for containing a fluid at a predetermined fluid level mounted in the vehicle body, 15 an air inlet means for admitting air into the tank below the predetermined fluid level, a suction conduit connected to the intake fuel conduit of the motor for drawing air from above the fluid level in the tank, a valve for controlling 20 the suction of the air from the tank, and a thermostat for controlling said last mentioned valve.

10. In a vehicle having a closed body compartment, the combination of an internal combustion motor unit provided with an intake conduit for 30 fluid fuel, and an air cooling device comprising a tank for containing a fluid at a predetermined fluid level mounted in the vehicle body, an air inlet means including a check valve for admitting air into the tank below the predetermined 35 fluid level, a suction conduit connected to the intake fuel conduit of the motor for drawing air from above the fluid level in the tank, a valve for controlling the suction of the air from the tank, and a thermostat for controlling said last mentioned valve.

11. In a vehicle having a closed body compartment, the combination of an internal combustion motor unit provided with an intake conduit for fluid fuel, and an air cooling device comprising a tank for containing a fluid at a predetermined fluid level mounted in the vehicle body, a supply conduit for communicating with a fluid supply and with said tank, an air inlet means for admitting air into the tank below the predetermined fluid level, a suction conduit connected to the intake fuel conduit of the motor for drawing air from above the fluid level in the tank, a valve for controlling the suction of the air from the tank, and a thermostat for controlling 50 said last mentioned valve.

12. In a vehicle having a closed body compartment, the combination of an internal combustion motor unit provided with an intake conduit for fluid fuel, and an air cooling device comprising a tank for containing a fluid at a predetermined fluid level mounted in the vehicle body, a supply conduit for communicating with a fluid supply and with said tank, an air inlet means including a check valve for admitting air into 60 the tank below the predetermined fluid level, a suction conduit connected to the intake fuel conduit of the motor for drawing air from above the fluid level in the tank, a valve for controlling the suction of the air from the tank, and a thermostat for controlling 65 said last mentioned valve.

13. In a vehicle having a closed body compartment, the combination of an internal combustion motor unit provided with an intake conduit

- for fluid fuel, and an air cooling device comprising a tank for containing a fluid at a predetermined fluid level mounted in the vehicle body, a supply conduit for communicating with a fluid supply and with said tank, a cut-off valve for controlling communication of the supply conduit with the tank, a float operative responsive to the fluid level in the tank for actuating the cut-off valve, an air inlet means for admitting air into the tank below the predetermined fluid level, and a suction conduit connected to the intake fuel conduit of the motor for drawing air from above the fluid level in the tank, said air inlet means including a control valve adapted to keep the air inlet closed when the cut-off valve of the fluid supply conduit is open, and to open the air inlet means responsive to the suction means when said cut-off valve is closed.
14. In a vehicle having a closed body compartment, the combination of an internal combustion motor unit provided with an intake conduit for fluid fuel, and an air cooling device comprising a tank for containing a fluid at a predetermined fluid level mounted in the vehicle body, a supply conduit for communicating with a fluid supply and with said tank, a cut-off valve for controlling communication of the supply conduit with the tank, a float operative responsive to the fluid level in the tank for actuating the cut-off valve, an air inlet means including a check valve for admitting air into the tank below the predetermined fluid level, a suction conduit connected to the intake fuel conduit of the motor for drawing air from above the fluid level in the tank, and a valve for controlling the suction of the air from the tank, said check valve of the air inlet means being operative to maintain the air inlet closed when the cut-off valve

of the fluid supply conduit is open, and to open the air inlet means responsive to the suction means when said cut-off valve is closed.

15. In a vehicle having a closed body compartment, the combination of an internal combustion motor unit provided with an intake conduit for fluid fuel, and an air cooling device comprising a tank for containing a fluid at a predetermined fluid level mounted in the vehicle body, a supply conduit for communicating with a fluid supply and with said tank, an air inlet means for admitting air into the tank below the predetermined fluid level, a suction conduit connected to the intake fuel conduit of the motor for drawing air from above the fluid level in the tank, a valve for controlling the suction of the air from the tank, and a thermostat for controlling said last mentioned valve.

16. In a vehicle having a closed body compartment, the combination of an internal combustion motor unit provided with an intake conduit for fluid fuel, and an air cooling device comprising a tank for containing a fluid at a predetermined fluid level mounted in the vehicle body, a supply conduit for communicating with a fluid supply and with said tank, a cut-off valve for controlling communication of the supply conduit with the tank, a float operative responsive to the fluid level in the tank for actuating the cut-off valve, an air inlet means including a check valve for admitting air into the tank below the predetermined fluid level, a suction conduit connected to the intake fuel conduit of the motor for drawing air from above the fluid level in the tank, a valve for controlling the suction of the air from the tank, and a thermostat for controlling said last mentioned valve.

FRED A. HELFRECHT.
